QUADRUPLE 20 MILLIMETER GUN MOUNT
MECHANISM FOR CONTROLLING THE
AIMING OF A GUNJohn M. Ewart, Beverly, Mass., assignor to United
Shoe Machinery Corporation, Flemington, N. J.,
a corporation of New Jersey

Application September 16, 1948, Serial No. 49,614

1 Claim. (Cl. 89—41)

1

This invention relates to mechanism for controlling the aiming of a gun, and more particularly to means by which gun movements in azimuth and elevation may be directed from either of two control stations and, upon occasion, an operator at one of these stations may render the other control station inoperative. It will be recognized that application of the invention is not necessarily restricted to mechanism for controlling guns but may well have other uses such as, for example, in control mechanism for mounts for search lights or sound receivers.

When employing rapid-fire guns against fast moving targets, it is commonly desirable that one man of a gun team serve as gunner while a second man be in a position to assist in tracking targets, charge the guns with ammunition, or perform other miscellaneous duties. Preferably, both men should have within easy reach of their respective stations the means whereby either can assume complete control of the laying and firing mechanisms. Should the gunner become disabled, or his controls damaged or for any other reason rendered ineffective, the continuance of effective firing requires that his assistant shall immediately take over control without interference from the gunner or hinderance from his inoperative post. The assistant's control grips must in these circumstances remain maneuverable even though debris prevents movement of the gunner's grips or they are being wielded aimlessly.

One object of the invention, therefore, is to provide improved dual control mechanism for a gun mount such that a gun or guns supported thereon may be operated at will from either of two spaced control stations, and a gunner at either one of these stations may, in emergency, maintain maneuverability of the mount by rendering the other station inoperative. To this end, a feature of the invention resides in the provision of independently operative means by which either of the two gunners may control hydraulically powered gun movement in azimuth and elevation and either may energize a solenoid to "free" or disengage the mount from the other's control so as effectively to assume complete control himself.

The above and other features of the invention including novel combinations of elements and arrangement of parts will be more particularly described in connection with one embodiment, reference being had to the accompanying drawings, in which

Fig. 1 is a side elevation of a quadruple gun

2

mount (some portions being broken away) having control mechanism illustrative of the invention;

Fig. 2 is a rear elevation of a portion of the gun mount, portions of the housings being removed to show more clearly the mechanism of the spaced controls;

Fig. 3 shows a diagrammatic view in perspective of the azimuth and elevation driving mechanism, the linkages connecting said mechanism with the control grips, and the solenoid-operated mechanism;

Fig. 4 is a sectional detail view taken on the line IV—IV of Fig. 1 and showing azimuth and elevation drive pumps with a portion of their control mechanism;

Fig. 5 is a plan view of the power control cam mechanism;

Fig. 6 is a view in front elevation of the mechanism shown in Fig. 5;

Fig. 7 is a detail in plan of the dither mechanism indicated in Figs. 5 and 6;

Fig. 8 is a detail, portions being broken away for clarity, showing an enlarged view in elevation of solenoid-operated mechanism;

Fig. 9 is a section on the line IX—IX of Fig. 8, the frame and securing bolt being in dash lines for clarity, showing the mounting of the centering springs and levers;

Fig. 10 is an enlarged view in elevation, with parts broken away, of a control stand seen in Fig. 1;

Fig. 11 is a plan view taken along the line XI—XI of Fig. 10;

Fig. 12 is a view partly in elevation and partly in section, on an enlarged scale, of one pair of the control grips shown in Fig. 2;

Fig. 13 is a section taken on the line XIII—XIII of Fig. 12; and

Fig. 14 is a wiring diagram of the circuits pertinent to the invention.

The words "right" and "left" are hereinafter used to indicate direction respectively to the right or to the left of the gunners when they face the gun mount and are in their normal operating positions.

The illustrated gun mount comprises a circular metal base 20 (Fig. 1) adapted to be bolted to the floor of a tank chassis or to any other movable or stationary supporting structure. Concentric with and secured to the interior of the base 20 is a conventional azimuth fixed ring gear 22, partially indicated in Fig. 3. A circular plate 24 (Fig. 1) is mounted on the base 20 in suitable manner to allow the mount rotation

through 360° in azimuth. As will hereinafter appear, the mount includes a plurality of gun assemblies, azimuth and elevation driving mechanism, and controls therefore, all supported by the plate 24 for rotation therewith.

The plate 24 serves as a platform for a pair of spaced standards 26 (only one of which is shown in Fig. 1) that extend upwardly, supporting in conventional manner a pair of twin gun assemblies G mounted in gun adapter housings 28, and a segment gear 30, the guns being adapted to be swung in unison with the gear 30 about the horizontal axis of trunnions not shown but journaled in the standards.

Near the rim of the plate 24 and the breeches of the guns are the control stations each being provided with a control stand 32 and a gunner's chair 34. Also supported by the plate 24 and easily reached by a gunner from either chair 34 is a central control housing 36 (Fig. 2) on which are mounted electrical control switches 38, 40 and 42 for functions later to be described. Transversely extending housings 44 and 46 together with a pump housing 47 secured on the platform 24 protect mechanism for driving the guns in azimuth and in elevation, and linkages connecting the aforementioned control stations with the driving mechanism.

The hydraulic power means for rotating the mount in train and moving the guns in elevation together with the power control linkages are shown schematically in Fig. 3. An electric motor diagrammatically indicated in Fig. 14 may receive electric energy from any suitable source, such as a tank's generators and batteries, and drive through a shaft 48 (Fig. 3) an enclosed gear train and shafts 49 and 50 to run an azimuth driving hydraulic pump 52 and an elevation driving hydraulic pump 54, respectively. It will be understood that a fluid reservoir (not shown) may be affixed to the platform 24 and connect with the hydraulic drive system. Fluid flow from the azimuth pump 52 and elevation pump 54 is conducted by suitable piping to an azimuth hydraulic motor 56 and an elevation hydraulic motor 58, respectively, the rates of flow to the azimuth and elevation motors being regulated by an azimuth control valve 60 and an elevation control valve 62.

As shown in Fig. 3 the motor 56 rotates the platform 24 in azimuth by driving a worm 64 and drive gears 66, 68, the latter extending downwardly through an opening in the platform to mesh with the azimuth fixed ring gear 22 within the base 20. In similar manner the motor 58 may drive a shaft 70 to each end of which is affixed a drive gear 72 in mesh with one of the two segment gears 30, the segment gears thereby being swung to elevate or lower the four guns G in unison.

For governing the laying of the guns, settings of both the azimuth and elevation pump control valves 60 and 62 may be adjusted from either of the aforementioned control stations, the respective valves having similar but independently operative linkages connecting with the control handles or grips in each of said stations as will now be described. In view of the practically identical structure and operation of the right and left-hand gunner's means for laying and firing the guns, as indicated by the drawings, wherein identical elements bear like reference characters, it will suffice in this regard to restrict the description to the right hand gunner's control mechanism. The control stand 32 (Figs. 1,

2, 4 and 10) supports the lower portion of an elevation shaft 74 for rotation in a bearing 76, the upper portion of the shaft 74 extending into a housing 78. A horizontal member 80, seen in Fig. 12, extends through and is rotatably mounted in the housing 78 to carry a pair of gunner's control grips 82 in handle-bar fashion. A finger 84 (Fig. 10) nonrotatably secured to the member 80 projects therefrom to straddle a cylindrical collar 86 which is slidable on the shaft 74. The collar 86 is provided with three spaced annular ribs 88. The two upper ribs form a channel in which the finger 84 holds for engagement therewith a roll 90. A roller 92 arranged to ride in the channel formed by the two lower ribs 88 is supported by one arm of a bell crank 94 that is pivotally connected to the forked upper end of a pin 96. The other arm of the bell crank 94 has a ball and socket connection with a lever 98, the latter having a similar connection with a lever 100 affixed to the elevation shaft 74.

The pin 96 extends downwardly through an arcuate slot 102 (Fig. 11) in the base of the housing 78, through a flange 112, and is locked against movement in a socket 104 provided in a fixed hub 106 of the stand 32 by a pin 108. The arcuate slot 102 is concentric with the shaft 74. The housing 78 is accordingly permitted to turn about the shaft 74 as an axis when so moved by the grips 82, and in so rotating, the housing 78 likewise turns an azimuth shaft 110, the flange 112 being integral with said shaft and screwed to the base of the housing 78 (Fig. 12). The azimuth shaft 110 concentrically surrounds the elevation shaft 74 but is rotatable independently thereof, being supported in a bearing 114 formed in the hub 106 and a ball bearing 116 mounted in a lower portion of the housing 32.

Arms 118 and 120 (Fig. 3) affixed respectively to the shafts 110 and 74 are pivotally connected respectively, by means of links 122 and 124, to the locking arms 126 and 128 of disconnecting mechanism (Figs. 8 and 9) now to be described. Beneath each gunner's chair and within the housing 46 is the solenoid actuated means by which the grip controls 82 may be operatively disconnected from the above-mentioned azimuth and elevation valves 60 and 62 while the other gunner's grips 82 are effectively locked to their linkages for independently controlling these valves. A frame 130 (Figs. 4, 8 and 9) secured to the plate 24 supports a solenoid 132 having a stem affixed to an arm of a bell crank 134 pivotally mounted on the frame 130 to operate a slide lever 136 journaled therein. A vertical fulcrum stud 138 having a shoulder 137 (Fig. 8) is secured by a bolt 139 to horizontal portions of the frame and passes through a slot in a block 140 which is integral with the lever 136. Concentrically arranged for pivotal movement about the stud 138 are the hubs of composite bell cranks which respectively comprise control levers 142, 144 and the cooperating locking arms 126, 128. Telescopically mounted for endwise projection from a horizontal bore 146 in each of the locking arms 126, 128 are spring-pressed, hollow or thimble-like plungers 148, 150 respectively. Stop pin 152, 154 affixed at right angles to the respective plungers 148, 150 project toward each other through oppositely disposed slots 156, 156 in the locking arms 126, 128 and are normally engaged by the arcuate perimeter of the block 140 though the composite bell cranks may be disposed at different angles about the stud 138. The slots 156 define the extent to which the plungers may be displaced in one direc-

tion in the bores 146 by the block 140. The displacement thus allowed is adequate for unseating the conical detent portions of the plungers from matching holes in the respective hubs of the control levers 142, 144 and then the locking arms 125, 128 are free to swing about the stud 138 independently of the control levers 142, 144 respectively. When in their locked or operative positions the plungers hold the locking arms of the composite bell cranks in fixed angular relation to the corresponding control levers.

Also mounted for pivotal movement about the stud 138 for purposes hereinafter explained is a pair of oppositely disposed upper centering levers 158 (Fig. 9) and a pair of similar lower levers 160 (Fig. 8). Upper and lower pairs of centering tension springs 162, 164, respectively, extend from projections on the frame 130 to oppositely disposed ears on the levers 158, 160. Stop lugs 163, 165 are secured to the locking arms 126, 128, respectively, and stationary lugs 166 are affixed to the frame 130 to enable the springs always to return the levers 158, 160 to what may be considered their central or neutral positions. The arrangement is such that a lug 163 and a lug 165 extend between and are engageable with the upper centering levers, and likewise lower lugs 163 and 165 extend between and are engageable with the lower centering levers. Each spring 162 or 164 consequently acts yieldingly to maintain engagement of a centering lever 158 or 160 with a pivotal stop lug 163 when a locking arm is swung, and accordingly the arm is always under tension to return to its central or neutral position. Thus it will be seen that the composite bell cranks always tend to resume their neutral positions when permitted to do so by the control grips 82 and, if the locking arms are not acting as a part of these bell cranks because their plungers 149, 150 are unseated, these arms still resume neutral positions wherein the composite bell cranks may again be formed.

An azimuth rod 168 is connected to the upper control levers 142 and an elevation rod 166 is connected to the lower control levers 144 of the two disconnecting mechanisms. Within the motor drive housing 44 (Fig. 4) is a dual series of independently movable links which effectively transmit control movements of the azimuth rod 168 and the elevation rod 166 to the azimuth control valve 60 and the elevation control valve 62, respectively. Since the structure and arrangement (Figs. 3, 4, 5 and 6) for opening or closing the valve 62 corresponds to that provided for adjusting settings of the azimuth valve 60, only the latter will now be described. A reciprocable azimuth valve stem 170 (Figs. 5 and 7) is connected by pivot pins to one end of a lever 172 by a link 174. The lever 172 (Fig. 7) is fulcrumed on a movable vertical pivot pin 176 and has a yoke end adapted to be engaged by an eccentric 178. The latter is one of two cams rotatably driven by a dither drive shaft 180 (Figs. 3, 5 and 6) continuously powered by the motor drive gear train. The lever 172 is thus caused to oscillate with an amplitude that is insufficient to disturb desired settings of the azimuth valve but renders it promptly responsive to azimuth control movements which may be transmitted by either set of control grips 82 via the azimuth rod 168 as will be seen. A housing 182 for the dither mechanism supports a bracket 183 holding a stationary pivot stud 184 (Fig. 5) on which a bell crank 186 is mounted, one arm of the crank having an end holding the pivot pin 176 and a longer arm extending to

support a cam roll 188. The latter engages a curved cam slot 190 in an arm of a bell crank 192, the slot being formed to secure movements of the valve stem 170 in accordance with azimuth movements of the control grips. The bell crank 192 is pivoted at 194 to the platform 24 and has a lower arm 196 which is pivotally connected to the azimuth rod 168. A corresponding arm of the bell crank for transmitting elevation control movements to the elevation valve is similarly connected to the elevation rod 166.

As hereinafter described, elevation stop mechanism in the not unusual arrangement shown in Fig. 1 is used to prevent either gunner from elevating the guns more or less than desired limits. The range of these limits is represented by the distance spacing two stop screws 200 affixed to the right hand segment gear 30 (Fig. 1), and an intermediate stop lever 202 is fulcrumed upon a gun adapter housing 28. The lever 202 is in a position to be contacted by either of the screws 200 and is pivotally connected to a turnbuckle rod 204. An end of the latter is received by a crank 206 carrying a bevel gear arranged to mesh with a gear 208, the turning of which moves a slotted link 210 (Figs. 3 and 4). A stop stud 212 secured to an elevation bell crank 214 (corresponding to the bell crank 192 in the azimuth linkage) is slideable in the slot of the link 210. The arresting movement of the guns by one of the stop screws 200 pivotally moving the lever 202 slides the link 210 to shut off the elevating power as will be seen hereinafter and this action is accompanied by the operation of simple shock absorbing mechanism now to be described. A projection of the lever 202 (Fig. 1) is engageable with a piston rod 216 mounted in a cylinder 218 supported by the housing 32. The cylinder 218 encloses two springs (not shown) oppositely engageable with a piston on the rod 216 and they thereby yieldingly hold said piston in a position intermediate the length of the cylinder 218.

The firing mechanism for each gunner's station includes a fire treadle 220 (Fig. 1) and a right and left-hand finger trigger 222 (Fig. 13), the triggers being arranged to actuate micro-switches 224 (Fig. 12) in the control grips 282. Conveniently, each grip also has an action lever 226 (Fig. 11), slight hand pressure on one of which is adequate to close a micro-switch 228 and thus commence operation of an electric motor for driving both the azimuth and elevation hydraulic pumps 52, 54. Referring to Figs. 2 and 13, the toggle switch 38 is the main switch controlling electrical energy from the source of supply and the switch 40 is a safety to be closed only when the gun mount is to be operated. The switch 42 when thrown to the right activates the right hand gunner's control grips 82 and energizes the solenoid 132 under the left-hand gunner's chair. If the control switch 42 be thrown to the left, the left-hand gunner's grips are activated or made "alive" and the other solenoid 132 beneath the right-hand gunner's chair is energized. A suitable motor relay 230 and a firing solenoid relay 232 are included as indicated in Fig. 14.

In operating the gunmount, switches 38 and 40 having been closed, a gunner may assume control of firing and laying the guns from his station by throwing the switch 42 toward himself. He fires the guns by depressing treadle 220 or a trigger 222. He controls azimuth movement of the mount by rotating his grips horizontally to the right or left of a neutral position which corresponds to a closed position for the azimuth

valve 60, and effects elevation or depression of the guns to the desired extent by raising or lowering the control grips 82 from a neutral position corresponding to the closed position of the elevation valve 62. It will be seen that his azimuth control movement turns the housing 78 (Fig. 10), and with it the azimuth shaft 110 thereby pivotally moving the locking arm 126 and the control lever 142 as a unit or bell crank to shift the azimuth rod 168. Similarly, it will be seen his elevation control movement of the grips 82 rotates the elevation shaft 74, the collar 86 being raised or lowered thereon by the grips to pivot the crank 94 and thus rotatably shift the bell crank 100. As the shaft 74 is turned with its lever 120, the lower locking arm 128 and control lever 144 are thereby pivotally moved as a unit to shift the elevation rod 166. Shifting of the rods 168, 166, which is accomplished by maneuvering the grips at either of the control stations, effects gun control hydraulically in azimuth and in elevation by setting the azimuth and elevation valves 60, 62, respectively. Each of the valves is changed in its setting by the above-described linkage which extends from the respective valve stems via the bell crank 186 and the cam slot 190 to its actuating rod 166 or 168. The moving of a control grip 82 in any direction from neutral is accordingly translated into azimuth and elevation valve settings allowing rates of pressure fluid flow to operate the azimuth and elevation drive motors 56 and 58 respectively, thus laying the guns. Fluid flow and, consequently, gun aiming will be at a more rapid rate when a grip is rotated further from its neutral position. When the control grip is returned, either manually or upon release, to its neutral position the valves are closed and fluid flow ceases. By reason of the above-described dithering mechanism which overcomes static friction load on the valve stems and because of the lack of lost motion in the linkages moved by the control grips 82, a reversal in the direction of grip movement immediately obtains a resetting of the azimuth and elevation valves and corresponding change in direction of the fluid flow driving the hydraulic motors 56, 58.

Operation of the gunner's controls as just related assumes the solenoid actuated disconnecting mechanism under his chair has permitted the plungers 148, 150 to remain seated within the hubs of the control levers 142, 144 (the condition shown in Fig. 8). If occasion arises for the gunner's assistant to assume sole control of the guns at his station, he need only throw the two-way triple-pole selector switch 42 toward himself thereby disrupting the other gunner's controls and effectively connecting his own with the firing mechanism and the valves 60, 62. Upon so throwing the switch 42, the assistant energizes the solenoid 132 under the gunner's chair and deenergizes the solenoid 132 under his own chair. The energized solenoid acts to slide the adjacent block 140 against both stop pins 152, 154 so as to unlock the plungers 148, 150 simultaneously from their respective seats and thereafter movement of the gunner's grips is ineffective for firing or transmission of control movements to the levers 142, 144 and on to the valves. The deenergized solenoid, however, permits its adjacent block 140 to be returned to normal position with the adjoining spring plungers 148, 150, the latter again locking with the control levers 142, 144 for transmission of control movements directed by the

assistant. An important feature to be noted is that in both disconnecting mechanisms when hands are taken off the control grips 82 the springs 162, 164 which are tensioned during grip movements to the right or left of neutral, will coat with the centering levers 158, 160 to return the locking arms 126, 128 and connecting control grips 82 to a neutral or power-shut-off position. On aiming his guns upon a target, the gunner may release the action levers 226 from contact with a microswitch 228 so that fluid flow to the driving motor is stopped and the guns will not be driven beyond the desired position in either azimuth or elevation.

As the guns approach limits of elevation or depression under hydraulic power one of the stop screws 200 will engage the lever 202 causing it to shift the rod 204 and thereby turn the crank 206. Rotatory movement of the latter transmitted through the gear 208 slides the slotted link 210. When the stop stud 212 is engaged by an end of the slot in the link 210, the bell crank 214 is forcibly pivoted to move the linkage connecting with the elevation valve stem. On reaching maximum gun elevation the arrangement is such that this stem is moved forwardly to close the valve 62, and the control grips 82 with connecting linkage will be automatically forced to return to their corresponding neutral position for elevation. When maximum depression of the guns is about to be reached the elevation valve stem will be forcibly retracted to its neutral position in the pump 54 by the other end of the slot in the link 210 and again the elevation control linkage will return the grips 82 to corresponding neutral position for elevation. By means of the cylinder 218 and its springs for centering the piston enclosed therein, the piston rod 216 is yieldingly displaced as the lever 202 is engaged by either of the limit screws 200. Accordingly, the shock of braking the mount during elevation is somewhat absorbed, a less sudden thrust is transmitted to the link 210, and the action of the springs in tending to recenter the piston is an aid to the gunner when he manipulates his control grips so as to reopen the elevation valve 62 for withdrawing the guns from their extreme positions of elevation or depression.

Having thus described my invention, what I claim as new and desire to secure by Letters Patent of the United States is:

In a gun mount including hydraulic motors for training a gun on the mount in azimuth and elevation, valves for controlling said motors, a control stand located on each side of said gun and spaced therefrom, a control panel located on said mount and accessible from either control stand, a set of control grips on each control stand, mechanical connections including horizontally extending rods leading from said grips to said valves, said connections including a disconnecting mechanism for each set of grips, each disconnecting mechanism including a pair of bell cranks normally having their respective arms locked for azimuth and elevation control movements about a common fulcrum, means for simultaneously unlocking the arms of one of said pairs of bell cranks a solenoid operatively connected to each disconnecting mechanism for actuating said means, and a switch on said control panel for controlling said solenoids whereby an operator at either of said control stands may

disconnect the connections leading to the grips on the other control stand.

JOHN M. EWART.
